M. E. DAVIS, OF FOLSOM, CALIFORNIA, ADMINISTRATRIX OF THE ESTATE OF M. C. DAVIS, DECEASED.

Letters Patent No. 92,520, dated July 13, 1869.

IMPROVEMENT IN CAN-OPENERS.

The Schedule referred to in these Letters Patent and making part of the same.

To all whom it may concern:

Be it known that M. C. DAVIS, deceased, late of Folsom, in the county of Sacramento, and State of California, did, during his lifetime, invent a new and improved Can-Opener; and I, Mrs. M. E. DAVIS, of Folsom aforesaid, administratrix of the estate of the said M. C. DAVIS, deceased, do hereby declare that the following is a full, clear, and exact description thereof, which will enable others skilled in the art to make and use the same, reference being had to the accompanying drawings, forming part of this specification.

This invention relates to improvements in implements for opening tin cans, by cutting a circular piece out of their ends, whereby, by the employment of a peculiarly-formed knife, arranged to be adjusted to cut holes of any size, on a radial arm, having a centre-pin for thrusting through the can, to serve as the fulcrum, around which the knife is caused to rotate on the said radial arm, it is designed to provide a simple and cheap implement, which will accomplish the work with greater facility than those now in use.

In the accompanying drawings—

Figure 1 represents an elevation of my improved implement, as it appears when being operated.

Figures 2 and 3 represent detailed views.

Similar letters of reference indicate corresponding parts.

A represents a hand-lever or radial arm, having a centring-pin, B, at one end, to be inserted in the centre of the piece to be cut out, to serve as a fulcrum for the said radial arm.

The outer end of the said arm A may be curved, as at C, to facilitate the holding of it in the hand, in connection with the knife-holding arm D, arranged to slide thereon.

The inner end of the arm or handle D is provided with a knife, E, of the form represented in plan, fig. 2, secured to the said handle at an angle thereto, whereby, when the implement is in the cutting-position, it will project through the sheet-metal in a manner to cause the least amount of friction to the cut edges of the sheet-metal on the faces of the same.

If, for instance, it projected through the said metal perpendicularly to the surface of the same, it could not separate the cut edges to provide room for itself in the direct line of the metal, the resistance in that line being obviously very great, but would have to bend the said edges either up or down, which would be accomplished after the knife has been set into rotary motion with great difficulty, the force of the knife being applied to the metal also in the line of its great-

est resistance, and perpendicular to the line of resistance of the said edges on the faces of the knife.

But when adjusted in the angular direction, as represented, the edges of the cut metal will be easily bent, the one up and the other down, sufficiently to afford room for the said knife, as will be readily understood, thereby affording the least amount of resistance to the operation of the cutter.

But when the knife is first thrust through the metal, it can be accomplished easier by a movement in the direction perpendicular to the metal, the force being applied in a manner to bend the severed edges directly downward; and for this reason the handle of the cutter is so arranged as to vibrate on the arm A sufficiently to present the point of the cutter perpendicular to the surface of the can when it is thrust in, and also for causing the point of the cutter to project further downward than the point of the axial pin B, which is preferably brought down and inserted afterwards, when the two handles are grasped in the right hand and turned to the left, while the can is held in the left hand.

To prevent any tendency of the resistance of the metal to throw the knife upward and out of the cutting-position, the cutting-edge is made angular, forming a projecting point, a, from which to the heel it will have a tendency to draw inward; and the cutting-edge is otherwise so shaped that it will describe a circle slightly greater than the heel, to prevent undue friction therein of that part of the can not cut out, which will not yield to the action of the knife in separating the two cut edges to provide room for its path as readily as the other portion, especially if cut near the outer edge of the can.

F and G represent pins or studs to limit the movement of the handle D on the arm C.

I claim as new, and desire to secure by Letters Patent—

1. The combination of the radial arm A, having the centre-pin B, with the handle D, supporting the cutter E, and adjustably arranged thereon, substantially as and for the purpose specified.

2. The cutter E, arranged to be thrust through the metal in a direction perpendicular thereto, and adjusted to the inclined position relatively to the same when cutting, substantially as and for the purpose specified.

The above specification signed by me, this 5th day of March, 1869.
